RAILWAY TRUCK

Donald S. Barrows and Glenn F. Couch, Rochester, N. Y., assignors to The Symington-Gould Corporation, Rochester, N. Y., a corporation of Maryland

Application February 12, 1946, Serial No. 647,139

25 Claims. (Cl. 105—203)

1

This invention pertains to a railway truck and more particularly to a flexible type thereof.

An object of the invention is the provision, in a railway truck, of an improved bolster-side frame connection which will allow the side frame to execute a "hobby-horse" or rocking action relative to the bolster.

Another object of the invention is the provision, in a railway truck, of an improved bolster and side frame connection which will permit a relative rocking motion between the side frame and bolster, arrest a horizontal angular movement therebetween and resist a transverse rocking motion therebetween.

A still further object of the invention is the provision, in a railway truck, of a side frame having a demountable chair interlocked therewith at a bolster opening thereof and a bolster end mounted directly on the chair in such a manner as to incorporate a quick wheel change feature in the bolster-side frame connection and to afford a rolling or rocking action of the side frame and chair relative to the bolster in a fore and aft direction or longitudinally of the truck with substantially no relative movement therebetween transversely of the truck.

The above and numerous other objects of the invention will become apparent from the succeeding description of an exemplified form of the invention which is illustrated by various views in the accompanying drawings which form a part of the present description and wherein:

Figure 1 is a partial side elevational and partial vertical sectional view of a railway truck embodying the present invention.

Figure 2 is a partial plan and partial horizontal sectional view of the railway truck shown in Figure 1 and being considered along the lines 2—2 thereof in the direction as indicated by the arrows.

Figure 3 is an enlarged sectional view taken along the lines 3—3 of Figure 1, looking in the direction of the arrows.

Figure 4 is a sectional view taken along the lines 4—4 of Figure 3, looking in the direction of the arrows.

Figure 5 is an enlarged sectional view taken along the lines 5—5 of Figure 1, looking in the direction of the arrows.

Figure 6 is a horizontal sectional view taken along the lines 6—6 of Figure 4 and looking in the direction of the arrows.

Figure 7 is a vertical sectional view taken along the lines 7—7 of Figure 3 and looking in the direction of the arrows.

2

Figure 8 is an outline side elevational view showing some of the components of the railway truck in an abnormal position.

Referring now in detail to the drawings, wherein like reference characters indicate like parts, the numeral 1 is employed to designate, in a general manner, a railway truck embodying the present invention. The railway truck generally comprises a side frame 2 light of weight, rigid, strong and simple in design and which preferably has its ends 3 formed with housings 3a to accommodate structure similar to that disclosed and claimed in the application for Letters Patent of D. S. Barrows, Serial No. 630,230, filed November 23, 1945, for Railway Truck. To this extent, therefore, the illustrated side frame is supported resiliently by journal boxes (not shown) spaced longitudinally of the truck. It will, of course, be clearly understood that the side frame illustrated is only one of a pair employed in a truck and that each railway truck includes a side frame at each transverse side thereof but, for the sake of brevity, only one side frame will be herein illustrated and described.

15 The side frame comprises a top or compression member 4 and a bottom or tension member 5 both of which unite at or adjacent the respective ends 3 to continue therebeyond to form suitable housings 3a for the accommodation of supporting and associated mechanisms which may be as clearly taught in the application of D. S. Barrows supra. The compression member, intermediate its ends, is formed of general inverted U-shape in vertical cross section to present a horizontal web 6 having depending from the transverse edges thereof, flanges 7 which terminate in reentrant flanges 8. The tension member is, what might be classified as, a catenary, double truss type of load carrying member in that it is formed as an integral member with a curved bottom portion 9 and oppositely extending upwardly inclined end portions 10 tangential with the curved portion. The tension member has an outer or lower truss 11 comprising inner and outer side flanges 12 having their maximum depth intermediate their ends at or adjacent to a transverse vertical plane of the truck which is characterized by the diagrammatic line A—A in Figures 1 and 4 of the drawings. Preferably for the entire length of the tension member the lower truss flanges are united by a bottom flange 13 which follows the contour of the lower edges of the flanges along the catenary line.

40 The compression and tension members are joined intermediate their ends by a pair of guide

columns 14 spaced a predetermined distance apart to form a central window opening 15 therebetween. Between each end 3 and a related guide column there appears a side opening 15a of triangular formation and defined by the compression member, a sloping portion of the tension member and a guide column. The lower truss side flanges merge, adjacent their top edges, into reentrant flanges 16 which extend inwardly of the side frame for a predetermined distance. A top or inner truss 17 is formed integrally with the bottom or lower truss and, between the guide columns, presents a substantially flat or horizontal shelf 18 having depending therefrom transversely spaced inner flanges 19 which merge with the free or inner extremities of the reentrant flanges therebeneath (see Figures 3 and 4). As the inner flanges progress from the transverse vertical plane of the truck they meet the related guide column where they are stepped transversely or outwardly of the side frame as at 19a and thus continue as at 19b longitudinally of the side frame where, at or about the center of the side window they feather out into the reentrant flanges along the inclined portions of the tension member. Preferably at a point within the limits of the window opening the flat shelf continues longitudinally of the side frame through the guide columns as upwardly curved tie plates 20. Each of these tie plates is bifurcated as at 21 within the area of the related column and continues as a gusset 22 upwardly along the inclined portion of the tension member to blend into or merge with the reentrant flanges at or about the same location as the feathering out of the inner flanges.

Each guide column is preferably channel-shaped in horizontal cross section and as such includes a vertical web 23 merging horizontally into transverse vertical inner and outer flanges 24 and 24a respectively. The column flanges form in effect downward continuations of the compression member flanges 7 and are in vertical alignment with and joined to the parts 19b of the top truss inner flanges.

Reverting to the general description of the side frame housing a little more detailed description thereof may be required to clarify the side frame design which forms a part of the present invention. The housing at each end of the side frame is defined at its upper limits by the web 6 of the compression member following the lines of an ogee or reverse curve as at 3b and which reaches its greatest height at a predetermined distance toward the window opening from a transverse vertical plane passing through the center of a related axle (not shown) as indicated by the vertical diagrammatic line B—B in Figure 1 of the drawings. The merged flanges of the compression and tension members form longitudinally spaced jaws 3c opening toward one another and defining therebetween a transverse opening 3d for the accommodation of a journal box (not shown).

The gussets 22 of the tension member, as they approach an apex of the triangular side opening again merge as at 3e to follow, for a predetermined distance, the outline of the side opening and at a required elevation is directed horizontally and toward a related end of the side frame to form longitudinally spaced spring seats 3f. As the spring seat forming web reaches the end of the side frame it is directed downwardly and vertically to form an end wall 3g of the related jaw. It will be here noted that the extension of

the compression member web merges as at 3h with the spring seat forming web as it is directed downwardly to form the end wall 3g. An end wall 3i of the other jaw is formed by bottom flange 13 being, in the area of the outer apex of the triangular side opening, directed downwardly and vertically. A final observation in connection with the housing design is that the outer jaw at each housing is terminated a slight distance below a horizontal axis of an axle as indicated by the diagrammatic line C—C in Figure 1 while the companion jaw extends an appreciable distance below this same horizontal axis. The jaws are thus designed because at the present writing it is believed necessary to provide a safety or tie means with the inner jaw only such as at the hanger 3k to engage a part of the journal box and thus limit a vertical separating movement of the journal box and side frame. When the journal box strikes the safety means it will be canted slightly so that an upper outer corner thereof may strike the outer jaw at or about a location indicated by the arrow 3m. By this arrangement, therefore, a considerable saving in weight is effected and the moment which tends to break off the outer pedestal or jaw is materially reduced.

Removably mounted upon the tension member within the lower area of the window opening is a chair or adapter casting 25 which forms an interlock between the side frame and a bolster 26 and performs numerous functions which will be hereinafter made apparent. The chair or adapter casting is provided with a lower or base wall 27 presenting a flat, plane or downward facing surface 28 arranged normally to bear directly upon the correspondingly disposed surface 18a of the inner truss of the tension member. If during assembly of the component parts of the truck or after extended service runs thereof it is found that the center plate (not shown) carried by the bolster intermediate its ends is not disposed at a required elevation so as to maintain a proper coupler height then, and in that event, shims (not shown) and of any required thickness may be introduced between the chair surface 28 and tension member surface 18a. This addition of shims will raise the chair and bolster and consequently the center plate to a desired or required height.

Forming an interlock between the chair or adapter casting and the inner or top truss of the side frame is a pair of side wall extensions or ribs 29 which overlie the flat shelf of the inner truss inwardly and outwardly thereof. This straddling effect of the chair not only prevents a shifting or unwarranted displacement of the chair transversely of the truck but, as will be noted, a housing is thus formed at the juncture of the surfaces 28 and 18a so that any shims placed at this location will be positively retained in operable position.

Rising vertically from or a predetermined distance above the transverse edges of the chair base wall and preferably in alignment with the ribs 29 are transversely spaced inner and outer walls 30 and 30a; the inner walls of which extend longitudinally of the truck a sufficient distance so as to permit the introduction of the chair into the window opening (see Figure 7), that is to say, the length of the inner wall is a trifle less than the distance between plane faces 23a of the columns and because of this arrangement or design the chair can be cupped over the tension member inner truss from the outside

of the truck and also it will be obvious from the above that its removal for the purpose of inspection, shimming, etc. may be made from the same side of the truck. The outer wall 30a of the chair is, on the other hand, extended horizontally beyond the clear opening into the window opening to thereby present outer lugs 31 which abut the column outer flanges 24a outwardly thereof and thus afford an added guard against the chair being, in service, displaced inwardly of the truck. Extending horizontally between and joining the upper limits of the chair inner and outer walls is a bearing or top wall 32 which is of the same width transversely of the truck as its companion base wall and also desirably terminates short of the columns to permit assembly of the chair and side frame. Extending vertically and transversely of the truck are a series of reinforcing walls 33 which join all the other walls of the chair to reinforce it against stresses to which it will be subjected in service. The ends 34 of the bearing wall are, adjacent the columns, made relatively flat as at 35 while an intermediate portion 36 is somewhat elevated or raised above the ends to thereby present a bearing wall of stepped arrangement for the purpose to be hereinafter made apparent (see Figure 7).

Forming substantially the sole connection between spaced side frames of the present railway truck is a bolster 26 which has an undisclosed portion of usual design in that it extends between the side frames and is provided with a usual center plate (not shown), intermediate its ends 38. The bolster, which functions as a transom as that component is recognized in the art, has an end portion 38 extending into an associated side frame window opening 15 with each end portion comprising vertically spaced substantially horizontal top and bottom walls 39 and 40 respectively joined integrally adjacent their transverse limits by vertically directed horizontally spaced side walls 41.

In the particular art to which this invention appertains it is well known that surfaces upon which wheels of a railway truck roll are not at all times in the same or a constant plane. That is to say, contiguous rail ends oftentimes present steps, up and down, over which a wheel must traverse. Steps are also present in rail crossovers, switches, etc. and due to these and other irregularities in the rails along a right of way it is not uncommon for one or more wheels of a four wheel truck to drop below or raise above the level of the remaining wheels of the truck. Recognizing these existing and unavoidable conditions as the cause of the side frames, during running service, executing a rocking action often referred to by those skilled in the art as a "hobby-horse" action because the side frames simulate such an action, means has been incorporated in the bolster-side frame connection so as to permit, within certain predetermined limits, the side frame to follow the vertical action of the supporting wheels. The reason for favoring or perhaps it might be said accommodating the side frame "hobby-horse" action is to relieve the components of the railway truck of abnormal stresses and, in addition to other reasons quite apparent, to insure, so far as it is practically possible, a constant full and complete bearing between the center bearings or plates (not shown) of the truck and body bolsters (not shown), as well as provide the truck with easy riding qualities.

Toward the accomplishment of the above there is formed on the intermediate portion of the chair bearing plate a concave, cylindrical upwardly facing surface 42 of a given or predetermined curvature. The bottom wall 40 of the bolster end is provided with a convex, cylindrical, downwardly facing surface 43 which is desirably and preferably of less radius than the curvature of the chair bearing plate (see Figure 7). The convex bolster surface bears directly upon the chair concave surface and is, considering a direction transversely of the truck, coextensive therewith. Theoretically, the actual contact between the curved surfaces lies normally in or adjacent to the vertical transverse plane of the side frame—line A—A—with the concentrated load from the transom formed bolster to the side frame passing normally through this vertical plane and received by the side frame at or adjacent to the center of the catenary double truss tension member. Thus, by so forming the bearing areas or surfaces between the bolster end and chair, a rolling movement will be executed by the side frame and still maintain or establish an adequate bearing area between the bolster and chair. Further, it may be here observed that due to the broad transverse contact between the arcuate bolster and chair surfaces 43 and 42 any vertical angling tendency of the bolster relative to the side frame will be positively resisted.

Contacting surfaces on the bolster and side frame to limit the side frame roll may be arranged in various relationships such as substantially truly vertical surfaces on the side frame columns to be engaged by surfaces on the bolster side walls spaced from and disposed at an angle to the column vertical surfaces. Another common expedient is to form truly vertical surfaces on the bolster side walls spaced from but disposed at an angle to inclined surfaces on the guide columns. By these methods or surface relationships attempts are made to bring about a surface contact between the bolster and side frame to limit a movement therebetween. It has been found in actual practice that the surface dispositions as above described do not, at all times, function as intended because the side frame and bolsters are not machined at the columns and portions of the bolster intended to contact the columns. While it might be intended that a full and complete surface bearing be effected between the columns and side walls of the bolster, conditions might be such that, as the side frame rolls under the bolster, only the bottom edge or corner of the side wall wall contact the column and under this condition the bolster will have a tendency to overturn under an impact directed longitudinally of the car body. With the above undesirable possibly existing conditions in mind the inner surfaces 23a of the columns are formed truly vertical so that the side defining surfaces of the window opening are parallel to one another. The bolster side walls 41 have formed thereon outer surfaces 44 which are spaced a predetermined distance away from the plane parallel surfaces 23a of the columns. These outer wall surfaces 44 are, for a greater part thereof, disposed in a vertical plane and parallel to one another and to the column surfaces 23a; being spaced a sufficient distance from the column surfaces to avoid, at any time, a contact between the parallel portions of these related surfaces. For a relatively small distance down from the top of the bolster the outer surfaces 44 thereof are inclined or slope inwardly of the bolster as at

45 with these inclined portions being disposed at an angle to the remaining vertical portion of the related outer surface. As clearly indicated in Figure 8 of the drawings, any complete rolling action of the side frame relative to the bolster will result in a surface bearing relationship between the column surface 23a and the bolster inclined surface 45 only and by reason of this construction and relationship the area of reaction between the side frame and bolster is definitely raised or located at an elevation very close to a horizontal plane of a center plate to defeat any tendency of a bolster to overturn.

It is well known in the art that during running service the bolster and side frames of a railway truck are subjected to external impulses which tend to shift these components relative to one another longitudinally of the truck. By way of example, the bolster tends to shift relative to the side frame when shocks are imparted to the car body through the coupler, and the side frames tend to move horizontally relative to a bolster when the wheels pass over contiguous rails, crossovers, switches, etc. These shocks may be of such intensity as to urge one surface 44 of the bolster into abnormal intimate contact with an opposing column surface 23a which, in such instances would alter the relationship between the cylindrical surfaces 42 and 43. To avoid other than a rolling action between the convex and concave surfaces there is provided, in the present structure, a holding means which will maintain a predetermined relationship between the side frame and bolster. Various types of holding means may be incorporated in a structure embodying the present invention but at the present writing it is preferred to employ a toothed arrangement. Accordingly, the holding means is herein characterized by a series of teeth 46 which lie in a circular path such as in an internal gear and are formed integrally with the chair. As herein illustrated, but not so necessarily limited, the chair is provided with two parallel paths of teeth; one path at each transverse side of the chair concave surface and formed at or near the juncture of the chair bearing plate and inner and outer walls. While the chair teeth do not or are not intended to carry any vertical load they are, however, subjected to horizontal shear and bending stresses and accordingly it is deemed advisable to embed the teeth in the chair so that the dedendum of the teeth indicated at Z in Figure 3 is below the concave surface and the addendum of the teeth indicated at Y is above the concave surface (see Figure 3). This disposition of the teeth, therefore, places the pitch circle or line of the teeth of each row in the same arcuate path as the concave surface so that substantially the strongest part of the teeth is subjected to the service shearing and bending forces. The portion of the chair at the base of each row of teeth is sloped outwardly and downwardly of the chair as at 47 to thereby function as a drain for the escape of any foreign matter which might find its way between the working surfaces of the teeth.

The chair teeth being thus formed as segments of an internal gear, each bolster end is also provided with a double row of teeth 48 which are spaced oppositely from and intermesh or interlock with the chair teeth. What has been said regarding the office of the chair teeth is equally applicable in connection with the bolster teeth because they cooperate to maintain a predetermined relationship between the bolster and chair. Accordingly, each row of bolster teeth is em-

bedded in the bolster with the dedendum of the teeth of each row and as indicated by the character X extending from the line of curvature of the bolster convex surface inwardly of the bolster and the addendum of the teeth of each row as indicated by the character W extending from the convex surface line of curvature downwardly or outwardly of the bolster. The pitch circle or line of each row of bolster teeth is as above indicated coincident with the line of curvature of the bolster convex surface. To further reinforce the bolster teeth against service stresses there is provided at each row, a rib-like shroud 49 which in fact is in each case a continuation or extension of the bolster bottom wall and further functions as a shield directing foreign matter away from the intermeshed teeth.

It will here be noted that the rows of teeth on the bolster and chair not only prevent a sliding or shifting action between the bolster and side frame or chair but they also prevent the bolster from executing a horizontal pivotal movement relative to the side frame. In this regard the railway truck may be considered or classified as of a rigid type at least insofar as one side frame is prevented from assuming a position out of transverse alignment with a companion side frame. Aside from this one feature of rigidity the truck, of course, will be recognized as of an extremely flexible type since the bolster-side frame connection allows a relatively wide range of adjustability in response to service side frame movements.

The present or illustrated construction is also desirably of a quick wheel change type and in this regard it will be observed by referring particularly to Figure 6 that no outer lugs are provided on the bolster to prevent the free withdrawal of a bolster end from the window opening inwardly of the truck; it being recalled that the outer guides 31 on the chair function as a means for preventing an accidental horizontal separation of the chair and consequently the bolster and the side frame. To limit movement of the bolster outwardly of the side frame there are provided guide lugs 50 on the bolster side walls inwardly of the truck from the side frame. These guide lugs which extend longitudinally of the truck are positioned in close proximity to the columns so that any transverse external impulses will pass between the side frame and bolster through the guides 50 and columns.

As previously stated the ends of the chair bearing wall are formed relatively flat as at 35 and these portions are spaced a sufficient distance below correspondingly disposed or relatively flat portions 51 of the bolster bottom wall so that as the side frame and chair roll below the bolster end there will be no contact between the portions 35 and 51 to interfere with such rolling movement. Upstanding vertically from the flat chair portions are posts or studs 52 formed integrally with the chair and extending through suitable accommodating apertures 53 in the bolster bottom wall. Locking means, cotters or keys 54 are associated with or threaded through the studs adjacent their upper free extremities to thereby present a safety device guarding against an accidental or unwarranted separation of the bolster, chair and side frame.

From the above it will be noted that various changes and alterations may be made to the described and illustrated exemplary structure without departing from within the spirit of this invention and scope of the appended claims.

We claim:

1. In a spring plankless truck, the combination of, a side frame presenting a window opening, a chair interlocked with a portion of said side frame, a concave surface on said chair, upwardly extending teeth on said chair, a load carrying member having an end extending into said window opening, a convex surface on said load carrying member end; said convex surface being of shorter radius than and bearing upon said concave surface, and downwardly extending teeth on said load carrying member end meshing with said teeth on said chair for resisting horizontal angling movement between said load carrying member and chair.

2. In a spring plankless truck, the combination of, a side frame presenting a window opening, a chair interlocked with a tension member of said side frame, a concave surface on said chair, upwardly extending teeth on said chair, a bolster extending into said window opening, a convex surface on said bolster of shorter radius than and bearing upon said concave surface, and downwardly extending teeth on said bolster meshing with said teeth on said chair; pitch lines of said teeth meeting at the contact between said convex and concave surfaces.

3. In a spring plankless truck, the combination of, a side frame presenting a window opening, a chair interlocked with a tension member of said side frame, a concave surface on said chair, teeth on said chair having a pitch line approximating the curvature of said concave surface, a bolster extending into said window opening, a convex surface on said bolster of less radius than and bearing upon said concave surface, and teeth on said bolster intermeshing with said chair teeth; said bolster teeth having a pitch line approximating the curvature of said convex surface.

4. In a spring plankless truck, the combination of, a side frame presenting a window opening, a chair interlocked with a tension member of said side frame, a concave surface on said chair, teeth partially within said chair, a bolster extending into said window opening, a convex surface on said bolster of less radius than and bearing upon said concave surface, and teeth formed partially within said bolster and intermeshing with said chair teeth for maintaining said chair and bolster against relative horizontal angling movement.

5. In a spring plankless truck, the combination of, a side frame presenting a window opening, a chair interlocked with a tension member of said side frame, a concave surface on said chair, teeth partially within said chair, a bolster extending into said window opening, a convex surface on said bolster of less radius than and bearing upon said concave surface of said chair, and teeth formed partially within said bolster and intermeshing with said chair teeth; a pitch line of said chair teeth coinciding with said concave surface, and a pitch line of said bolster teeth coinciding with said convex surface for maintaining said chair and bolster against relative horizontal angling movement.

6. In a spring plankless truck, the combination of, a side frame presenting a window opening, a catenary type tension member defining the lower limits of said window opening, a concave surface formed on said tension member within said window opening, teeth carried by said tension member and maintained in a predetermined position relative to said tension member, a bolster extending into said window opening and having a convex surface arranged to roll on said concave

surface, and teeth adjacent said convex surface and carried by said bolster for engaging said first named teeth.

7. In a spring plankless truck, the combination of, a side frame presenting a window opening, a double truss catenary type tension member defining the lower limits of said window opening, a concave surface carried by said tension member within said window opening, teeth carried by said tension member and maintained in a predetermined position relative to said tension member, a bolster extending into said window opening and having a convex surface arranged to roll on said concave surface, and teeth adjacent said convex surface and carried by said bolster for engaging said first named teeth; said surfaces being arranged to carry the entire vertical load passing from said bolster to said side frame tension member.

8. In a spring plankless truck, the combination of, a side frame presenting a window opening, a double truss tension member defining the lower limits of said window opening, a lower truss of said tension member being of a catenary type and an upper truss of said tension member presenting a flat surface, a chair interlocked with said upper truss and having a flat surface bearing upon said first named flat surface, a concave surface on said chair above said flat surface, a bolster extending into said window opening, a convex surface on said bolster of less radius than and bearing upon said concave surface, and means on said bolster and chair for preventing a horizontal shifting of said bolster relative to said chair longitudinally of said side frame.

9. In a spring plankless truck, the combination of, a side frame presenting a window opening, a double truss tension member defining the lower limits of said window opening, a lower truss of said tension member being of a catenary type and an upper truss of said tension member presenting a flat surface between columns of said side frame, a chair interlocked with said upper truss and having a flat surface bearing upon said first named flat surface, a concave surface on said chair, a bolster extending into said window opening, a lower convex surface on said bolster of less radius than and bearing upon said concave surface, and interlocking means on said bolster and chair for allowing a rolling motion of said chair relative to said bolster and arresting a horizontal angular movement of said bolster relative to said chair.

10. In a spring plankless truck, the combination of, a side frame presenting a window opening, a double truss tension member defining the lower limits of said window opening, a lower truss of said tension member being of a catenary type and an upper truss of said tension member presenting a flat surface between vertically faced columns of said side frame, a chair interlocked with said upper truss and having a flat surface bearing upon said first named flat surface, a bolster extending into said window opening between said vertically faced columns, contacting arcuate surfaces of different radii on said bolster and chair for affording a rolling action between said bolster and chair, and interlocking means on said bolster and chair for maintaining a predetermined relationship therebetween.

11. In a spring plankless truck, the combination of, a side frame presenting a window opening, a removable chair interlocked with a tension member of said side frame and occupying a lower area of said window opening, a bolster extending

into said window opening, contacting arcuate surfaces of different radii on said bolster and chair for affording a rolling action between said bolster and chair, and interlocking gear teeth on said bolster and chair for arresting a horizontal angular movement therebetween.

12. In a spring plankless truck, the combination of, a side frame presenting a window opening, vertically faced columns defining sides of said window opening, a removable chair mounted upon and stationary with respect to a tension member of said side frame, a bolster formed with contacting arcuate surfaces of different radii, a chair for affording a rolling action between said bolster and side frame, intermeshing means on said bolster and chair for arresting a horizontal angular movement therebetween, and surfaces on sides of said bolster disposed at an angle to and arranged to contact said vertically faced columns for limiting said rolling action.

13. In a chair for use in a railway truck, the combination of, a lower wall having a flat surface arranged to bear upon a correspondingly formed surface of a side frame, ribs inwardly and outwardly of said side frame extending below said flat surface for locking said chair to said side frame, a concave cylindrically formed surface spaced above said flat surface and disposed between vertical planes of said ribs, and studs upstanding from said chair and arranged to extend into a bolster; said concave surface being curved longitudinally of said chair.

14. In a chair for use in a railway truck, the combination of, a lower wall having a flat surface arranged to bear upon a correspondingly formed surface of a side frame, ribs inwardly and outwardly of said side frame extending below said flat surface for locking said chair to said side frame, a concave surface spaced above said flat surface, and gear teeth formed in said chair; said gear teeth extending above and below said concave surface; said concave surface being curved longitudinally of said chair.

15. In a chair for use in a railway truck, the combination of, a lower wall having a flat surface arranged to bear upon a correspondingly formed surface of a side frame, ribs inwardly and outwardly of said side frame extending below said flat surface for locking said chair to said side frame, a concave surface spaced above said flat surface, and gear teeth formed in said chair; the pitch circle of said gear teeth coinciding with the curvature of said concave surface.

16. In a bolster for use in a railway truck, the combination of, an end formed on said bolster, side walls of said end having vertical surfaces parallel to one another and terminating adjacent the top of said bolster in surfaces inclined inwardly of said bolster, said inclined surfaces being arranged to bear fully against adjacent surfaces on columns of a side frame to limit the angular movement of said bolster on said side frame, a convex surface on a bottom wall of said end, and a line of gear teeth formed transversely of and on said bottom wall.

17. In a bolster for use in a railway truck, the combination of, an end formed on said bolster, side walls of said end having surfaces disposed vertically and parallel to one another, upper limits only of said parallel surfaces merging with inclined surfaces, and a convex surface on a bottom wall of said end.

18. In a bolster for use in a railway truck, the combination of, an end formed on said bolster, side walls of said end having adjacent the top

thereof surfaces arranged at an angle to adjacent surfaces on columns of a side frame, a convex surface on a bottom wall of said end, and a line of gear teeth formed on said bottom wall; a pitch circle of said gear teeth being curved to coincide with said convex surface and a surface formed on said side frame on which said bolster may rock, said surfaces engaging the surface on the said frame to limit the rocking movement of said bolster.

19. In a railway truck, the combination of, a side frame presenting a window opening, a chair interlocked with said side frame within said window opening, an upwardly facing concave surface on said chair and curved longitudinally of said side frame, upwardly extending teeth at each side of said concave surface, a bolster having an end extending into said window opening, a convex surface on said bolster end bearing upon and of less radius than said concave surface, and downwardly extending teeth at each side of said convex surface and meshing with said upwardly extending teeth to prevent horizontal angling movement between said bolster and chair.

20. In a railway truck, the combination of, a side frame presenting a window opening, a chair interlocked with said side frame within said window opening, an upwardly facing concave surface on said chair and curved longitudinally of said side frame, upwardly extending teeth disposed transversely of said truck at each side of said concave surface, a bolster having an end extending into said window opening, a convex surface on said bolster curved longitudinally of said side frame and bearing upon said concave surface, said convex surface being of less radius than said concave surface, downwardly directed teeth disposed transversely of said truck at each side of said convex surface and meshing with said upwardly extending teeth to prevent horizontal angling of said bolster relative to said chair, and means on said chair within said window opening and extending into said bolster to prevent separation of said chair and bolster.

21. In a railway truck, the combination of, a side frame presenting a window opening, a chair interlocked with said side frame within said window opening, an upwardly facing concave surface on said chair and curved longitudinally of said side frame, upwardly extending teeth disposed transversely of said truck at each side of said concave surface, a bolster having an end extending into said window opening, a convex surface on said bolster curved longitudinally of said side frame and bearing upon said concave surface, said convex surface being of less radius than said concave surface, downwardly directed teeth disposed transversely of said truck at each side of said convex surface and meshing with said upwardly extending teeth to prevent horizontal angling of said bolster relative to said chair, and means on said chair at ends of said concave surface extending through apertures in said bolster for preventing vertical separation of said chair and bolster.

22. In a railway truck, the combination of, a side frame presenting a window opening, a chair interlocked with said side frame within said window opening, an upwardly facing concave surface on said chair and curved longitudinally of said side frame, a bolster mounted directly on said chair within said window opening, a convex surface on said bolster of less radius than and bearing upon said concave surface, said concave and convex surfaces being curved longitudi-

nally of said truck, a row of teeth at each side of said concave surface extending into said bolster from said chair, and a second row of teeth at each side of said convex surface extending into said chair from said bolster, said chair and bolster teeth being relieved of any vertical loads and offering resistance to a horizontal angling movement of said bolster relative to said chair.

23. In a railway truck, the combination of, a side frame presenting a window opening, a chair interlocked with said side frame within said window opening, an upwardly facing concave surface on said chair and curved longitudinally of said side frame, a bolster mounted directly on said chair within said window opening, a convex surface on said bolster of less radius than and bearing upon said concave surface, said concave and convex surfaces being curved longitudinally of said truck, a row of teeth at each side of said concave surface extending into said bolster from said chair, a second row of teeth at each side of said convex surface extending into said chair from said bolster, said chair and bolster teeth being relieved of any vertical loads and offering resistance to a horizontal angling movement of said bolster relative to said chair, and means at ends of said convex and concave surfaces for preventing vertical separation of said bolster and chair.

24. In a railway truck, the combination of, a side frame presenting a window opening, a chair interlocked with said side frame within said window opening, an upwardly facing concave surface on said chair and curved longitudinally of said side frame, a bolster mounted directly on said chair within said window opening, a convex surface on said bolster of less radius than and bearing upon said concave surface, said concave and convex surfaces being curved longitudinally of said truck, a row of teeth at each side of said concave surface extending into said bolster from said chair, a second row of teeth at each side of said convex surface extending into said chair from said bolster, said chair and bolster teeth being relieved of any vertical loads and offering resistance to a horizontal angling movement of

said bolster relative to said chair; a pitch line of said chair teeth being coincident with said concave surface, and a pitch line of said bolster teeth being coincident with said convex surface.

- 5 25. In a railway truck, the combination of, a side frame presenting a window opening, a chair interlocked with said side frame within said window opening, an upwardly facing concave surface on said chair and curved longitudinally of said side frame, a bolster mounted directly on said chair within said window opening, a convex surface on said bolster of less radius than and bearing upon said concave surface, said concave and convex surfaces being curved longitudinally of said truck, a row of teeth at each side of said concave surface extending into said bolster from said chair, a second row of teeth at each side of said convex surface extending into said chair from said bolster, said chair and bolster teeth being relieved of any vertical loads and offering resistance to a horizontal angling movement of said bolster relative to said chair, and studs up-standing from said chair adjacent ends of said concave surface and extending through apertures in said bolster for preventing vertical separation of said chair and bolster.

DONALD S. BARROWS.
